United States Patent Office

Des. 188,752
Patented Sept. 6, 1960

188,752

BOOT

Sidney Cohn, 1020 Crossland Ave., Clarksville, Tenn.

Filed Jan. 28, 1959, Ser. No. 54,368

Term of patent 7 years

(Cl. D7—7)

Fig. 2.

Fig. 1.

I claim:

The ornamental design for a boot, as shown.
